(57) **CLAIM**

The ornamental design for a combined LED light handheld mirror and charging base, as shown and described.

DESCRIPTION

FIG. 1 is a front, bottom perspective view of a combined LED light handheld mirror and charging base of my new design, shown in a first position;

FIG. 2 is a rear, top perspective view thereof;

FIG. 3 is a front elevation view thereof;

FIG. 4 is a rear elevation view thereof;

FIG. 5 is a left side elevation view, the right side elevation view being a mirror image;

FIG. 6 is a left side elevation view of the combined LED light handheld mirror and charging base, shown in a second position;

FIG. 7 is a top plan view thereof, shown in a first position; and,

FIG. 8 is a bottom plan view thereof.

The broken lines in the drawings illustrate portions of the article that form no part of the claimed design.

1 Claim, 8 Drawing Sheets
